F. A. PUTNAM.

TIMER.

APPLICATION FILED SEPT. 18, 1908.

925,649.

Patented June 22, 1909.

UNITED STATES PATENT OFFICE.

FRED A. PUTNAM, OF MELROSE, MASSACHUSETTS, ASSIGNEE TO SEWING MACHINE SUPPLIES COMPANY, OF BOSTON, MASSACHUSETTS, A CORPORATION OF MASSACHUSETTS.

EDITION.

No. 825,648.

Specification of Letters Patent.

Patented June 22, 1898.

Application filed September 18, 1896. Serial No. 462,582.

To all whom it may concern:

Be it known that I, FRED A. PUTNAM, a citizen of the United States, residing at Melrose, in the county of Middlesex and State 5 of Massachusetts, have invented an Improvement in Timers, of which the following description, in connection with the accompanying drawing, is a specification, like characters on the drawing representing like parts.

10 This invention relates to timers such as are used with internal combustion engines for regulating the time of the operation of the sparking plug.

The object of the invention is to provide a 15 timer with a novel movable contact member which is extremely simple in its construction and inexpensive to manufacture, and which will not be deteriorated by constant use.

Referring to the drawings, Figure 1 is a 20 front and side view of a timer embodying my invention; Fig. 2 is a rear elevation thereof; Fig. 3 is a front view with the cap removed; Fig. 4 is a partial section on the line $x-x$, Fig. 1; Fig. 5 is a section on line 25 $y-y$, Fig. 3.

The timer comprises a casing 3 which is sustained by a hub 4 and which is provided with a removable cap 5, said cap being secured to the casing in any suitable way, as 30 by means of the clamping screw 6. The cap 5 carries centrally thereof a contact 7 with which a wire 8 is electrically connected, and the sides of the casing carry a plurality of other contacts 9, to each of which a wire 10 35 is electrically connected. There are as many of these contacts 9 in the side of the casing

as there are cylinders in the engine, and the wires 10 of said contacts lead to the sparking plug or sparking coils of said cylinders in 40 a well known manner. The wire 8 connects with the battery or other source of electrical energy as usual. These parts are or may be of any well known construction and form no part of my present invention. I prefer, 45 however, to use ball contacts such as herein illustrated, in which the contact portion is a spring-pressed ball retained within a cage 11. It is not essential to my invention, however, 50 that the stationary contacts be of this particular construction, which is an old and well known one. In timers of this type a movable contact member is placed within the casing and is rotated therein in such a way as to bring it successively into engagement with 55 the various contacts 9, said rotary contact

member having a continuous electrical connection with the contact 7 in the end of the casing. One of the features of my present invention relates to the construction of this movable contact within the casing, which is in 60 the form of a roll 13 that is loosely mounted on a stud 14 that is carried by the bushing 15. The bushing 15 is rotatably mounted within the hub 4, and is rigid with the shaft 16 by which it is rotated, said shaft being 65 operated from any suitable or convenient part of the engine. The stud 14 is eccentrically arranged, that is, it is situated at one side of the axis of the shaft 16, and the eccentricity of said stud has such a relation 70 to the size of the roll 13 that as the bushing 15 turns the roll is brought into engagement with the contacts 9 in succession. The stud 14 is provided with the enlarged head 17 that has contact with the contact 7, said head 75 being of such a size that there is a constant contact between the head and the contact 7 in every position of the bushing. Since the contact roll 13 is loosely mounted on its stud it will follow that whenever it strikes any 80 one of the contact balls 9 it will have a slight turning movement and as a result a different portion of the surface of said contact roll is constantly being presented to the various contacts 9. This prevents the roll from becoming pitted or otherwise worn in any particular spot. Moreover, since the contact roll is loosely mounted on its stud it will have a rolling engagement with the stationary contacts 9, thus reducing friction and 85 preventing wear.

The casing is shown as being provided with an arm 18 by which it may be taken in usual manner to advance or retard the spark. This arm is shown as integral with 90 a ring 19 enclosing the casing and adjustably clamped thereto by means of the clamping screw 21, said arm 18 being slotted at 20 to permit of the clamping action. This manner of adjustably clamping the arm 18 100 to the casing forms no part of my present invention, however.

Various changes in the construction of the device may be made without departing from 105 my invention.

Having described my invention, what I claim as new and desire to secure by Letters Patent is—

1. In a timer, the combination with a casing having a contact in its end and a plu- 110

- rality of contacts in its side, of a rotary member extending into the casing and provided with an eccentrically-arranged stud having an enlarged head which is adapted at all times to engage the contact in the end of the casing, and a contact roll loosely mounted on said stud and adapted to engage the contacts in the side of the casing as said member rotates.
- 10 2. In a timer, the combination with a casing having a contact in its end and a plurality of contacts in its side, of a bushing rotatably mounted in said casing, an eccentrically-arranged stud sustained by said bushing, and a contact roll loosely mounted 15 on said stud and adapted to engage the contacts in the side of the casing as the bushing rotates, said stud having an enlarged head adapted at all times to engage the contact in the end of the casing. 20
- In testimony whereof, I have signed my name to this specification, in the presence of two subscribing witnesses.

FRED A. PUTNAM.
